UNITED STATES PATENT OFFICE.

OWEN B. LEWIS, OF BALTIMORE, MARYLAND.

FUSIBLE LINK FOR AUTOMATIC SPRINKLERS.

1,304,332.

Specification of Letters Patent.

Patented May 20, 1919.

Application filed May 13, 1918. Serial No. 234,262.

To all whom it may concern:

Be it known that I, OWEN B. LEWIS, a citizen of the United States, residing in the city of Baltimore and State of Maryland, have 5 invented certain new and useful Improvements in Fusible Links for Automatic Sprinklers, of which the following is a specification.

My invention is designed to provide a link 10 for automatic sprinklers of fire extinguishing systems and for like purposes which may be made economically, will be efficient and reliable in use and quickly assembled as to the two parts of which it is composed.

15 The invention consists in the features and combination of parts hereinafter described and particularly pointed out in the claims.

In the drawings:—

20 Figure 1 is a face view of the complete link.

Fig. 2 is a vertical section, taken on line 2—2 centrally thereof.

Fig. 3 is a cross sectional view on line 3—3 of Fig. 1.

25 Fig. 4 is a sectional view of one of the plates alone.

Fig. 5 is a view of the inside face of one of the plates.

The link is composed of two like members 30 or plates 1, 2. Each plate is formed with a central recess or pocket 3 of substantially hemispherical form and extending from this pocket on the inner face of the plate is a rib 4 which is formed by upsetting the metal 35 from the one face which I will call the outer face, inwardly so as to project from this latter face. The rib has divergent portions extending from the central pocket and these merge into parallel portions at 5 which are 40 connected by the cross portion 6 which has its ends terminating beyond the sides 5. The cross sectional shape of the rib is curved and this presents a rounded face without any sharp corners.

45 On the other side of the central pocket or recess the plate is provided with a groove or recess 7 formed by pressing the metal from the inner face of the plate outwardly and this recess is of the same general outline, 50 though reversed in position, to that of the rib above mentioned and this recess is of a width and of a cross sectional shape adapted to receive a rib like that above described on the second plate 2. This second plate 2 is of 55 exactly the same shape as plate 1. They are both made by the same die. In placing them

together they are reversed in position so that the recess groove or channel 7 of one plate will be opposite to and receive the rib 4 projecting from the other plate, so that the 60 plates will interlock and it will be necessary only to prevent them from separating from each other laterally in order that they may function as a composite link for resisting strong pressure either longitudinally or 65 transversely in an edgewise direction.

The means for holding them together includes a mass of solder at 8 filling the spherical recess formed between the pockets 3 of the two plates. When brought together and 70 interlocked by means of their ribs and grooves 4, 7, the two pockets 3 of the plates match and provide the recess in which the main mass of solder 8 is held.

In assembling the two plates to form the 75 link, one of the plates is laid flat on a suitable support and the mass or lump of solder of the proper size is laid in the recess 3 thereof and the other plate is placed in position with its recess 3 and ribs 4 and groove 80 7, matching the complementary parts of the first plate and then by applying heat sufficient to melt the solder the two plates will be united, some of the solder will flow between the plates covering all portions of 85 their opposed faces and their interlocking ribs and grooves though this covering will be in the form of a thin film and some of the solder may be squeezed out over the edges of the plates. Each plate has an extension 9 90 with an opening 10 to receive the strut of the sprinkler head. This link is intended for use with any suitable form of sprinkler head. The usual form has a pair of struts with laterally extending arms, which are 95 maintained in position, to hold the valve in place by the fusible link and my invention is adapted for use with this form of sprinkler head or any other form.

In use the ball of solder at the center of 100 the plates not only attaches the plates together, but it materially aids in resisting any movement of one plate on the other in an edgewise direction. Any tendency of the plates to move one on the other is also resisted by their ribs and grooves interlocking with each other.

The cross portion 6 of the ribs and grooves extend at right angle to the longitudinal axis of the link and hence at right angles to 110 the line of the main strain and this cross portion presents a long bearing for the parts.

The parallel portion 5 of the ribs and grooves resist tendency to separate in an edgewise direction transverse to the main longitudinal axis of the link while the divergent portions of the ribs and grooves resist tendency to separate in both a longitudinal and transverse direction. The channels 7 aid in the distribution of the solder between the plates. The solder exposed at the edges of 10 the plates receives the heat direct and conducts it to all other portions of the solder.

The two members of the link are interlocked by rounded surfaced ribs fitting in correspondingly shaped grooves and it will be observed 15 that there are no square or sharp interlocking corners which will tend to unduly retain the plates in their holding relation after the solder melts. On the contrary, the rounded interlocking parts will permit an instant 20 separation of the plates as soon as the solder ceases to function as a means to attach the plates together. So long as the plates are held in their proper relation the interlocking ribs and groove walls will effect- 25 tually resist tendency for one plate to be displaced edgewise in relation to the other and the interlocked portions take the direct strain and relieve the solder from stress.

I claim:—

- 30 1. A fusible link consisting of two plates placed face to face each having a cup shaped formation at its central portion which substantially register with each other, said plates each having a projecting portion and a recessed portion with the projecting portion of one fitting in the recessed portion of the other, whereby the plates are interlocked and solder in the recess formed by the cup shaped parts, substantially as described.
- 40 2. A fusible link consisting of two plates of like formation each having a cup shaped formation at its center, and each having a projecting portion and a recess at different parts of one face, said plates being placed together 45 face to face with one reversed in relation to the other so that the projection of each plate will fit in the recess of the other plate and solder in the space formed by the cup shaped parts, substantially as described.
- 50 3. A fusible link composed of two plates of like formation each having a cup shaped formation at its central part with a rib on one side of the cup shaped portion and a recess in the plate at the other side of the cup shaped part, said rib and recess being on the same face of the plate, said plates being arranged face to face so that their cup shaped portions will substantially register

and the rib on each plate will fit in the recess of the other plate and solder between the plates and in the cup shaped parts, substantially as described.

4. A fusible link composed of two plates of like formation each having a cup shaped formation at its central part with a rib on one side of the cup shaped portion and having a recess at the other side of the cup shaped part, said rib and recess being on the same face of the plate, said plates being arranged face to face so that their cup shaped portions will substantially register and the rib on each plate will fit in the recess of the other plate and solder between the plates and in the cup shaped parts, the said recess in each plate connecting with the cup shaped central recess thereof, substantially as described.

5. A fusible link composed of two like plates each having a central cup shaped part and having also a groove composed of divergent portions extending from the cup shaped part and a transverse portion connecting the divergent portions and a rib of similar form to the said groove but of smaller dimensions, said plates being placed face to face in reversed position with the rib of one plate fitting in the groove of the other plate and solder between the plates.

6. A fusible link consisting of two sheet metal plates, each having a central depression with a groove extending therefrom in a general direction lengthwise of the plate and with a transverse extension, and having a similar rib on the other side of the central depression and on the same face of the plate, said plates being reversed in position and placed face to face with the rib on each plate fitting in the groove of the other plate, substantially as described.

7. A fusible link consisting of two plates having registering recesses in their adjacent faces filled with solder, each of said plates having a rib on one face and a recess on its other face in line with the rib, and with the rib on each plate engaging the recess of the opposing plate, substantially as described.

8. A fusible link consisting of two plates with pockets formed near their central portions, registering with each other and containing a body of solder, each of said plates having distributing channels leading from said pockets, and each having ribs fitting in the channels of the opposing plates, substantially as described.

In testimony whereof, I affix my signature.

OWEN B. LEWIS.
